IRONING DEVICE

Edwin E. Foster, Austin, Tex.

Application November 17, 1932, Serial No. 643,092
Renewed March 27, 1934

27 Claims. (Cl. 68—9)

The present invention relates to an ironing device and particularly to a counterweighted or balanced iron. It is an object of this invention to construct a device to be attached or secured to an ironing board or to a wall or other support, so that the weight of the iron is counter-balanced and the influence of such counter-balance is removed while operating the iron. It is a further object of this invention to counterweight the iron support and also the iron itself, and to provide for adjustability of these two weights or counter-balances.

It is a still further object of this invention to remove the influence of the iron counterweight by a movement or manipulation of the handle of the iron through the arm supporting the iron when the iron has been moved adjacent the material to be ironed. Also the weight of the iron may be decreased or increased for a specific effective ironing pressure even when the iron is on the board.

Further objects will be apparent from the following description taken in connection with the accompanying drawings, in which:

Fig. 1 is a plan view of the ironing device according to one form of the invention showing by dot and dash lines the outline of the ironing board and also having certain parts removed.

Fig. 2 is a side view of the ironing device and board.

Fig. 3 is an end view partly in section of a detail taken on line 3—3 of Fig. 2.

Fig. 4 is a top view of a modified construction of an ironing device, and

Fig. 5 is a side view of the form of device shown in Fig. 4.

Referring to Figs. 1 to 3, the ironing board 1 is mounted on a metal plate or frame 2 by means of screws or the like, through the holes 37 and is supported upon a central leg 3 secured to the plate. The leg and board are preferably adjustable for height by means of a suitable base or tripod legs, not shown, having rollers on two rear legs. Fixed to the plate member 2 is a vertical and cylindrical guide rod 4 upon which a sleeve member 5 slides. This sleeve may be fitted with suitable bearings and is free to move up and down and also to revolve. The sleeve 5 carries and supports the linked arm 38 on which is mounted the iron 28. This arm consists of three rods or sections 6, 7 and 8 pivotally joined or linked end to end as shown. A chain or cord 9 secured to the arm 6 and the leg 3 prevents the arm 6 from revolving more than approximately 150 degrees around the rod 4.

The sleeve member 5 is provided with two discs 10 and 11 which are rigidly secured on the sleeve 5 in spaced relation to receive the rollers 12 and 13 therebetween. The roller 12 is mounted on one end of a guide lever 14 by means of a short axle 39, the lever having a bearing or fulcrum 15 mounted on a preferably hollow shaft 17. On the other end of the lever 14 a counterweight 16 is slidably mounted and this counterweight when nearest the fulcrum, as shown, is just sufficient to balance the weight of the sleeve 5 and arm 38 but not the weight of the iron itself. If the counterweight 16 is moved further away from the fulcrum, it will lift the weight of the arm 38 and sleeve 5, as well as a part of the weight of the iron 15 itself. Furthermore, the counterweight 16 acts upon the disc 10 tending to force the sleeve 5 upwardly at all times.

Another counterweight 18 is provided which acts with the counterweight 16 and supplies enough additional weight to balance the weight of the iron 28 itself. This counterweight 18 is slidably mounted on a second lever 19 cooperating with a connecting lever 20 having a short axle 40 and a roller 13 thereon contacting between the discs 10 and 11. The lever 19 is designed to cut out or remove the influence of the counterweight 18 at the desired time, which latter, however, varies due to the differences in thickness of the garments or materials that are ironed.

The two counterweights 16 and 18 are connected together by a member which is preferably in the form of a flexible wire 32 which is guided by the curved tubes 30 and 31 fixed to the brackets 33 and 34, respectively, and which latter are fixed to the levers 14 and 19, respectively. The shaft 17 is hollow to allow the wire 32 to pass therethrough. The object of this connection is to allow the effective weight of the counterweight 16 to be varied, but to cause the effective total weight of counterweights 16 and 18 to remain constant. The operator may make this change by moving the handle 35 or the handle 36 which is utilized to secure the ends of the wire to the counterweights. If the operator is left-handed the arm member 7 may be changed to the opposite side of the board. The counterweight 16 acts upon the disc 10 at all times. Counterweight 18 acts upon disc 10 to aid the weight 16 to lift the arm and iron assembly when the iron is being lifted, but is cut out while the pressing operation takes place.

The drawings show the iron half way between its extreme upper position and its lower position, which is approximately the surface of the ironing board. The lever supporting the counterweight 55

18 is made up of two sections, 19 and 20, each of which is pivoted about the fixed shaft 17. The lever 19 which carries the slidably mounted counterweight 18 on one end, is curved upwardly at its other end 41, Fig. 2, and on the end thereof is a pin 23. Lever 20 on the pivot end, which is the short end of this lever, is provided with a short connecting link 21 pivotally mounted at 26. This connecting link 21 has a roller 24 on its upper end which is adapted to roll against a cam 25, mounted on the plate member 2. As will be seen in Fig. 2, the pin 23 rides or is guided in the slot 22 of the link 21. The cam 25 is circular, with the center of the shaft 17 as the center of the circle. During the part of the stroke in which the roller 24 contacts against the circular section of the cam 25, the arms 20 and 19 will remain in a straight line, and the weight 18 will act upward upon the disc 10 to counter-balance the iron. When, however, the disc 10 is lowered by pushing down on the handle 27 of the iron to such an extent that the roller 24 rolls off the circular section of the cam 25, as shown at 24', the arm 20 may continue to move downward about its fulcrum 17 without, however, lifting the arm 19. In this position the influence of the counterweight is against the end surface 42 of the cam but not against the disc 10 thereby removing the influence of the counterweight 18 from the iron so that the iron will press its weight on the material to be ironed. When, however, the arm 38, member 5, and the discs 10 and 11 are again moved upward, the roller 24 will roll off the end surface 42 of the cam and onto the circular section 25, and thus the influence of the weight 18 will again be available for lifting the iron. Therefore, it will be apparent that the point of change has a definite relation to the position of the sleeve 5 upon the guide member 4.

As clearly seen in Fig. 2, the iron is not fixed rigidly to the arm 8. The iron may revolve and also move up and down with relation to arm 8. The handle 27 of the iron 28 acts as the long end of a lever to force the arm 8 downward after the iron itself is resting upon the surface of the ironing board 1 or on the material to be ironed. A compression spring 29 is provided which tends to lift the arm 8 upward with respect to the iron. Thus, when the iron is moved downward and allowed to touch the surface of the ironing board, the roller 24 should still be on the circular section of the cam 25, but at its very end just ready to roll off. Then when the weight of the operator's hand upon the lever handle 27 forces the arm 8 downward and in turn the arms 7 and 6 and the sleeve 5 still further, the roller 24 rolls off the circular section 25 of the cam, and the influence of the counterweight 18 is removed. The point of change occurs about half way of the stroke of the handle 27. Any difference in thickness of the material being ironed would vary this change point in relation to the stroke of the iron handle 27. For instance, if the garment is unusually thick the change would occur when the handle had been moved downward through approximately three fourths of its stroke instead of one half. Then when the weight of the operator's hand is removed from the handle 27, the spring 29 lifts the arm 8 past the change point and the iron again becomes counter-balanced.

The ironing device, therefore, will relieve the operator of the necessity of lifting the weight of the iron at any time. The weight of the iron is balanced by the counterweights and has the effect of being counter-balanced only during the time it

is being removed from or to the ironing board and is kept suspended while the garment is being arranged. Then when the iron is brought in contact with the board and the weight of the operator's hand is applied downward upon the handle of the iron, the influence of one of the counterweights is removed and the iron presses downward upon the garment with its own weight. The other counterweight continues to balance the weight of the flexible or jointed arm leading to the iron. Assuming that the iron weighs ten pounds and that the operator wishes the iron to have an effective weight upon the garment of less than ten pounds, then by a simple adjustment, that is, sliding the counterweights, the desired pressure is attained without disturbing the balanced condition of the iron when it is again removed from the board. In other words, as far as the operator is concerned, the iron appears to be counter-balanced and will remain suspended in mid-air, but its effective ironing pressure may be easily and quickly varied from a maximum to a minimum. The iron may be moved to any position upon the ironing board without affecting the balanced condition.

In the form of the invention according to Figs. 4 and 5, the ironing device is removably attached to the wall 50 instead of to the ironing board 1, in order that a special ironing board be not required. Thus the regular folding ironing board or drop board may be utilized. The arm 51 of the ironing device is patterned somewhat after the human arm with the bearing 52 as the shoulder, the bearing 53 as the movable elbow, and the joint 54 as the wrist. By placing the board in the correct location in relation to this fixed shoulder 52, any desired position on the board can be reached by the iron 28 as, for instance, is indicated by the dotted line position 55. When the iron is not in use it can be folded into a compact position against the wall as shown by dotted lines 56 in Figure 4. The ironing device may be removed from a fixed socket 57 which is screwed permanently to the wall 50.

The guide and sleeve arrangement of Figs. 1 and 2 have been replaced by a quadrilateral linkage preferably in the form of a parallelogram. The four pivot pins 53, 59, 60 and 61 permit the elbow spindle 53 to move vertically but to remain in a vertical position at all times. The pin 58 is the fulcrum of the arm or lever system. The horizontal levers 62 and 63 are of equal length and one is directly under the other. The lever 63 is utilized primarily to complete the linkage. The pin 61 revolves in the bearing 64 which preferably forms a part of the arm 65, but it is keyed or otherwise secured to the bar 62 and to the guide lever 66 by cotter pins or other suitable means. The bar 62 and the guide lever 66 always remain in a straight line and the counterweight 16 slidably mounted on the lever 66 always acts downward to lift the arm 51 upwardly. A second lever 67 is rotatably mounted on the pin 61 and is provided with a counterweight 18. A short arm 68 is preferably welded directly on the end of the pin 61, and it carries on its end a connecting pin 69. A connecting link 70 is pivotally mounted on the pin 69 and is provided with a slot 71 and a roller 72 on the end thereof. The lever 67 also has an upright lug 73 with a pin 74 secured thereto and projecting into the slot 71 of the connecting link 70.

The cam 75 is suitably secured on the arm 65 in such a position that it is directly above the 75

lug 73. This cam has two cam surfaces thereon, one surface 76 being curved and a shorter surface 77 being straight. The operation of these various elements is the same as described in connection with the construction according to Figs. 1 to 3 and that is that the second lever 67 remains in a straight line with the lever 62 and these two act as a plain lever rotating about the pin 61 as a fulcrum provided that the roller 72 contacts or rolls on the curved cam portion 76. However, when the levers 62 and 67 have rotated at the same time rotating the pin 61 and the arm 68 to such an extent that the roller 72 rolls off the curved cam portion 76 and onto the straight portion 77, the weight of the counterbalance 18 then acts directly against and on the straight cam section 77 but not on the arm 62 because of the slot 71 in the connecting link 70. As in the construction according to Figures 1 to 3, the counterweights 16 and 18 are adjustably mounted by sliding them simultaneously on their arms 67 and 66. The counterweights are connected to each other by means of a flexible wire 32 which is secured to a handle 35 for the counterweight 16, and a handle 36 for the counterweight 18. This wire 32 slides in a tube 78 which is secured on a support 79 on each of the arms 66 and 67.

The iron 28 is provided with a handle 27 which is pivotally mounted on a supporting member 80 about the pivot 81. Furthermore, the handle is provided with an operating lever 82 which has a right angle portion 83 and contacts in a spool-like member 84. When the iron is pushed down by means of the handle 27 so that it just contacts the board, a further pressure of the hand will cause the operating lever 82 to be moved downward which acts on the spool to move it down relative to the supporting member 80. This will cause the arm 51 to be moved down sufficiently so that the roller 72 rolls onto the straight cam surface 77 to thereby remove the influence of the counter-balance 18 from the iron. A tension spring 85 is connected at one end to the handle 27, and at the other end to the supporting member 80 so that the handle 27 will be lifted when the operator's hand is removed and thereby the roller 72 will roll from the surface 77 to the surface 76 in order to restore the weight of the counter-balance 18 on the iron. As in the construction according to Figures 1 to 3, the weight 16 is for the purpose of continuously counter-balancing at all times the weight of the arm 51 which of course includes the quadrilateral linkage, but weight 18 counter-balances merely the iron as stated.

As clearly shown in Figure 5, the arm 65 rotates around the bearing 52 which is on a short arm 86. This short arm 86 has a right angle member 87 which fits into the socket 57. The right angle member 87 is provided with suitable holes 88 so that the height of the ironing device can be adjusted in the socket by means of a suitable pin 89 which may be provided in any hole 88.

I claim as my invention:—

1. An ironing device comprising an iron having an operating handle; a counter-balanced arm for supporting the iron; and means operable by actuation of the handle relative to the iron and through the arm to remove the influence of the counter-balance after the iron has been moved adjacent the material to be ironed.
2. An ironing device comprising an iron having an operating handle; a linked arm on one end of

which the iron is secured; a counter-balance for the arm; a counter-balance for the iron; and means operable by the handle of the iron to remove the influence of the counter-balance for the iron, after the iron has been moved adjacent the material to be ironed.

3. An ironing device according to claim 2, in which the counter-balances are adjustably mounted relative to each other.

4. An ironing device comprising an iron having a pivoted operating handle; a linked arm on one end of which the iron is movably mounted; a sleeve for supporting the arm secured to the other end thereof; a counter-balance for the arm operable through the sleeve; a counter-balance for the iron operable through the sleeve; and means operable by the handle of the iron through the arm and sleeve to remove the influence of the counter-balance of the iron after the iron has been moved adjacent the material to be ironed.

5. An ironing device according to claim 4, in which the counter-balances are adjustable relative to each other.

6. An ironing device comprising an iron having an operating handle; a linked arm for the iron; a movable sleeve for supporting the arm; a counter-balance for the iron operable through the sleeve and arm; and means operable by the handle of the iron to remove the influence of the counter-balance after the iron has been moved adjacent the material to be ironed.

7. An ironing device comprising an iron having an operating handle; an arm for movably supporting said iron; counter-balance means for said arm and iron; and means operable by the handle of the iron through the arm to remove the influence of the counter-balance after the iron has been moved adjacent the material to be ironed.

8. An ironing device according to claim 7, in which the arm comprises a number of linked sections, and the counter-balance means comprises a pair of counter-balances of which one is for the arm and the other for the iron.

9. An ironing device comprising an iron having an operating handle; counter-balanced means for the iron; and means operable by actuation of the handle relative to the iron and through said first-named means to remove the influence of the counter-balance after the iron has been moved adjacent the material to be ironed.

10. An ironing device comprising an iron having a pivoted operating handle; a linked arm on one end of which the iron is movably mounted; a sleeve for supporting the arm secured to the other end thereof; a plate which is adapted to be secured to an ironing board; a guide rod vertically mounted on said plate and on which the sleeve is vertically movable; a counter-balance for the arm operable through the sleeve; a counter-balance for the iron operable through the sleeve; and means operable by the handle of the iron through the arm and sleeve to remove the influence of the counter-balance of the iron after the iron has been moved adjacent the material to be ironed on the board.

11. An ironing device according to claim 10, in which the counter-balances are adjustable relative to each other.

12. An ironing device comprising an iron having a pivoted operating handle; a linked arm on one end of which the iron is movably mounted; a sleeve for supporting the arm secured to the other end thereof; a plate which is adapted to be secured to an ironing board; a guide rod vertically

5 mounted on said plate and on which the sleeve is vertically movable; a pair of discs mounted in spaced relation on the sleeve; a pair of levers pivotally mounted on the plate and having one 10 end of each of them cooperating with the discs; a counter-weight mounted on the other end of each lever, one weight being adapted to counter-balance the arm and the other the iron; and means 15 operable by the handle of the iron through the arm, the sleeve, the discs, and the lever for the iron counterweight to remove the influence of the counterweight of the iron after the iron has been moved adjacent the material to be ironed on the board.

15 13. An ironing device according to claim 12, in which the counterweights are adjustably mounted on the levers relative to each other.

20 14. An ironing device according to claim 12, in which the lever for the iron counterweight is in two sections, one of which carries the counter-weight and the other contacts with the discs and both being pivotally mounted about the same pivot and in which means are provided so that the weight of the counterweight will not be transferred to the section of the lever which contacts with the discs when the iron is adjacent the material to be ironed.

25 15. An ironing device comprising an iron having a pivoted operating handle; a linked arm on one end of which the iron is movably mounted; a plate which is adapted to be secured to an ironing board; a guide rod vertically mounted on said plate and on which the other end of the arm is vertically movable and rotatable; a double 30 armed lever having a common pivot mounted on the plate and one section of the lever cooperating with the linked arm; a counterweight on the other section of the lever to counter-balance the iron; a cam on the plate; and means 35 operable by the handle of the iron through the arm, the lever, and the cam to remove the influence of the counterweight, after the iron has been moved adjacent the material to be ironed, by transferring the weight of the counterweight on the cam instead of the section of the lever cooperating with the linked arm, the section of the lever having the counterweight thereon having a curved up portion cooperating with a connecting link pivotally mounted on the other section of the lever, and the connecting link having a roller on the end thereof adapted to contact with the cam.

40 16. An ironing device comprising an iron having a pivoted operating handle; a linked arm on one end of which the iron is movably mounted; a plate which is adapted to be secured to an ironing board; a guide rod vertically mounted on said plate and on which the other end of the arm is vertically movable and rotatable; a 45 double armed lever having a common pivot mounted on the plate and one section of the lever cooperating with the linked arm; a counterweight on the other section of the lever to counter-balance the iron; a cam on the plate, the section of the lever having the counterweight thereon having a curved up portion cooperating with a connecting link pivotally mounted on the other section of the lever, and the connecting link having a roller on the end thereof adapted to contact with the cam; and means operable by the handle of the iron through the arm, the lever, and the cam to remove the influence of the counterweight, after the iron has been moved adjacent the material to be ironed, by transfer-

5 ring the weight of the counterweight on the cam instead of the section of the lever cooperating with the linked arm, the cam having a curved portion and a straight portion whereby when the roller which is controlled by the handle of the iron rides on the straight portion, the weight of the counterweight will bear against the cam instead of the other section of the lever.

10 17. An ironing device comprising an iron having an operating handle; an arm on which the iron is supported, including a quadrilateral linkage to permit the arm to be raised and lowered; a counter-balance for the iron cooperating through the arm and with the linkage; and means operable by the handle of the iron through the 15 arm and linkage to remove the influence of the counter-balance after the iron has been moved adjacent the material to be ironed.

18. An ironing device according to claim 17 in which the quadrilateral linkage is in the form 20 of a parallelogram.

19. An ironing device according to claim 17 in which means are included for removably mounting the device on a vertical wall.

25 20. An ironing device comprising an iron having an operating handle; an arm on one end of which the iron is movably mounted and including a linkage on the other end in the form of a parallelogram to permit the arm to be raised and lowered; a counter-balance means for the arm 30 cooperating with the linkage; a counter-balance means for the iron cooperating with the linkage; and means operable by the handle of the iron through the arm and linkage to remove the influence of the counter-balance of the iron after the iron has been moved adjacent the material to be ironed.

35 21. An ironing device according to claim 20, in which the counter-balances are adjustably mounted relative to one another.

40 22. An ironing device according to claim 20, in which a second arm is provided, a portion of which forms one side of the linkage and which is rotatably mounted on a short arm.

45 23. An ironing device according to claim 20, in which a second arm is provided, a portion of which forms one side of the linkage and which is rotatably mounted on a short arm, and in which a cam is mounted on the second arm and is provided with a curved portion and a straight 50 portion cooperating with one arm of the linkage so that when cooperating with the straight portion the weight of the counter-balance will be removed from the iron.

55 24. An ironing device comprising an iron having an operating handle; an arm on one end of which the iron is movably mounted and including a linkage on the other end in the form of a parallelogram to permit the arm to be raised and lowered; a counter-balance means for the arm 60 cooperating with the linkage; a counter-balance means for the iron cooperating with the linkage; a second arm provided with a portion thereof which forms one side of the linkage and which is rotatably mounted; a cam mounted on the second arm provided with a curved portion and a straight portion; a connecting link cooperating at one end with one of the bars of the linkage and contacting at the other end with the cam; and means 65 operable by the handle of the iron through the arm to remove the influence of the counter-balance of the iron after the iron has been moved adjacent the material to be ironed and when the connecting link moves from the curved portion 70

to the straight portion of the cam whereby the weight of the iron counter-balance is taken up against the straight portion of the cam.

25. An ironing device according to claim 9, in which means are provided to removably mount the device adjacent an ironing board.

26. An ironing device, comprising an iron having an operating means; an arm on which the iron is mounted and having counterbalance means for the iron; and means operable by actuation of the operating means relative to the iron and through the arm to remove the influence of

the counterbalance after the iron has been moved adjacent the material to be ironed.

27. An ironing device, comprising an iron; an arm on which the iron is mounted to permit lateral and vertical motions; counterbalance means for the iron associated with the arm; counterbalance means for the arm; and means operable from the iron through the arm to remove the influence of the iron counterbalance after the iron has been moved adjacent the material to be ironed. 5 10

EDWIN E. FOSTER.
